UNITED STATES PATENT OFFICE.

ISAAC T. PROSSER, OF CHICOPEE FALLS, MASSACHUSETTS, ASSIGNEE, BY MESNE ASSIGNMENTS, TO DRAPER CORPORATION, OF HOPEDALE, MASSACHUSETTS, A CORPORATION OF MAINE.

LOOM-CHEECE.

1,255,635.

Specification of Letters Patent.

Patented Feb. 5, 1918.

Application filed September 7, 1915. Serial No. 49,163.

To all whom it may concern:

Be it known that I, ISAAC T. PROSSER, a citizen of the United States, and resident of Chicopee Falls, county of Hampden, State 5 of Massachusetts, have invented an Improvement in Loom-Cheeces, of which the following description, in connection with the accompanying drawing, is a specification, like characters on the drawing representing like 10 parts.

This invention relates to improvements in picker checks for looms and the object thereof is to provide a more simple, efficient and economical picker check which may be 15 applied to the usual type of loom and which is particularly adapted for automatic filling replenishing looms in which it is necessary to arrest the shuttle precisely at a predetermined point.

20 The usual picker check comprises a picker strap in the form of a loop the opposite ends of which are engaged by the picker stick as it approaches the end of its oscillation in each direction, the picker stick driving the 25 strap through a frictional device of some character applied to the side of the loop. These check straps are necessarily formed of a high grade of leather and constant wear necessitates their renewal from time to time 30 at a considerable expense.

One of the objects of the invention is to provide a picker check in which a relatively inexpensive leather or other flexible material 35 may be utilized.

Another object of the invention is to provide a picker check with a frictional device 40 constructed of relatively movable rigid members which are less subject to wear and so constructed that the amount of friction 45 between the relatively moving surfaces may be easily and accurately adjusted and whereby the checking action may be uniform throughout the entire extent of the checking operation so that the picker stick will be 50 stopped without rebound or locking.

In the usual form of picker check above described the check strap has a creeping motion as it passes through the frictional member and as the picker stick is engaged by the 55 strap during the time this creeping takes place a torsional strain is placed upon the stick each time it engages the strap.

Another object of the invention is to provide a picker check in which such torsional 55 strain upon the picker stick is avoided.

This is accomplished by arranging the rigid frictional members in parallelism with the plane of oscillation of the picker stick and providing the movable member with a non-creeping flexible member adapted to be engaged by the picker stick. 60

Another object of the invention is to provide a picker check which will so arrest the shuttle that less tension will be required upon the spring of the binder in the shuttle 65 box. By thus arresting the shuttle by my improved picker check the power required to operate the loom is materially lessened and the wear upon the shuttle in the shuttle box is minimized to a great extent. 70

Other objects of the invention will more fully appear from the following description and the accompanying drawings and will be particularly pointed out in the annexed 75 claims.

The drawings illustrate a portion of one end of the lay of a loom and a portion of a picker stick with my invention applied thereto, one end only of the lay being illustrated, since the picker checks at both ends 80 thereof may be the same.

In the drawings; Figure 1 is a rear elevation of a portion of the end of the lay and of the picker stick with my invention applied thereto, 85

Fig. 2 is a detail vertical sectional view through the lay and central portion of the picker check.

Fig. 3 is a detail plan view showing the picker stick and a portion of the picker check 90 in section.

As illustrated in the drawing the lay 1, and shuttle box 2, having a binder 3, with the spring 4 for actuating the same, may be of the usual type and actuated in the usual 95 manner, the picker stick 5 extending through the slotted bottom of the shuttle box and being oscillated by any suitable mechanism not shown.

The improved picker check preferably 100 comprises relatively movable rigid frictional members one of which is provided with means adapted to be engaged by the picker stick during its oscillation in each direction. A preferred embodiment of the invention is 105 illustrated herein which comprises a stamped steel bracket and guide consisting of a flanged portion 6 secured to the side of the lay by a bolt or bolts 7 and having an offset portion 8 terminating in a channel 110

shaped guide, the parallel members 9, 10 of which form ways for a relatively sliding frictional member 11. This frictional member may conveniently be made of wood or other suitable material and may be provided with a wear plate 12 of leather, fiber board or other suitable frictional material. A bearing member 13 of wood or other suitable material, preferably rectangular in form is secured between the walls 9, 10 of the channel member, being prevented from longitudinal movements by sets of bolts 14, 15 extending across the channel and abutting against the ends of the bearing member 13.

In order to provide for increasing or decreasing the frictional engagement between the relatively movable members the member 13 desirably is pressed against the member 11 by a spring 16 one end of which may conveniently rest in a recess 17 in the central portion of the member 13 and the other end thereof against the head 18 of a screw 19 which may be supported in a yoke or bracket 20 secured to the walls 9, 10 of the guiding channel, the screw 19 being provided with a slot 21 at its end by means of which it may be adjusted toward and from the sliding member to provide the desired compression upon the spring 16, a set nut 22 providing means for locking the screw 19 in the desired adjustment.

While the mechanisms above described embody a preferred form of my invention the details thereof may be varied and any suitable friction adjusting means may be provided as will be readily apparent.

In order that the picker stick may engage a flexible or yieldable member, a check strap 25 which may be of leather, canvas, or other fabric is attached to the ends of the slide 11 preferably by a bolt 26 extending longitudinally through the slide 11, the ends of the strap 25 being secured at one end between the head 27 of the bolt and the end of the slide and at the other end between a suitable nut 28 and washer 29 and the opposite end of the slide. This check strap may be of a single piece of material or may be of a built up construction as illustrated in the drawing, comprising a continuous member extending from one end of the slide to the other and a plurality of overlapping shorter members secured thereto. By such construction pieces of relatively inexpensive material, such as scrap leather, canvas, fiber, or other suitable material which will yield gradually or sluggishly without causing the picker stick to rebound may be used, thus providing a very economical structure which may be readily replaced, when worn, at a minimum expense. As a matter of fact any suitable sluggishly flexible means may be secured upon the slide 11 to be engaged by the picker stick within the scope of my invention.

The channel guide and the frictional members desirably are arranged in parallelism with the plane of oscillation of the picker stick and consequently in parallelism with the path of the shuttle. By this arrangement a uniform frictional engagement is provided between the wear plate 12 of the sliding member 11 and the bottom of the channel bar and between the slide 11 and the frictional member 13 so that a uniform and effective restraint is applied to the picker stick which arrests the latter without rebound or locking. Furthermore, as the picker stick is restrained equally in both directions, its coöperation with the shuttle is most effective and the shuttle is brought to rest exactly at the desired point. This is particularly advantageous when my invention is used upon looms provided with automatic shuttle replenishing mechanism since in such case it is necessary that the shuttle shall be arrested exactly beneath the hopper or battery in such a manner that the rings upon the bobbins which are transferred from said battery to the shuttle will be thrust properly into the recesses in the jaws of the shuttle.

It will be obvious that by reason of the fact that the channel guide and bracket may be constructed of stamped or drop forged metal, and the frictional members constructed of rectangular pieces which are easily machined, the device may be constructed at a minimum of cost, furthermore these parts being of hard material wear slowly and by reason of their adjustability may be continued in use indefinitely, the only portion of the picker stick needing repair being the check strap, which as before stated may be constructed of relatively cheap material.

It will be understood that the embodiment of the invention disclosed herein is illustrative and not restrictive and that various changes in form, size, and proportions of the parts may be made and that other changes within the provisions of a skilled mechanic are within the scope of my invention.

Having thus described my invention what I claim as new and desire to secure by Letters Patent is:

1. A picker check for looms comprising a rigid guiding member, a rigid slide bar reciprocably mounted thereon, means for causing uniform frictional resistance to the movement of said slide bar throughout the extent of its reciprocation, whereby its movement will be gradually checked, and picker stick engaging members formed entirely of sluggishly flexible material connected to the slide bar at each end thereof and extending laterally therefrom into the path of the picker stick and adapted to bend when engaged by the picker stick and gradually to check its movement in each direc- 125 130 135 140 145 150 155 160 165 170 175 180

tion without causing the picker stick to rebound.

2. A picker check for looms comprising a rigid guiding member, a rigid slide bar reciprocably mounted thereon, adjustable means for causing uniform frictional resistance to the movement of said slide bar throughout the extent of its reciprocation, whereby the movement of the slide bar will be gradually checked, flexible members projecting laterally from the ends of said slide bar adapted to be engaged by the picker stick and a check strap connected to the ends of said slide bar overlying said flexible members.

3. A picker check for looms comprising a rigid guiding member, a rigid slide bar reciprocably mounted thereon, adjustable means for causing uniform frictional resistance to the movement of said slide bar throughout the extent of its reciprocation, whereby the movement of the slide bar will be gradually checked, a plurality of short pieces of flexible scrap material secured to and projecting laterally from the ends of the slide bar adapted to be engaged by the picker stick and a check strap overlying said piece of material and connected at its ends to said slide bar.

30 4. A picker check for looms comprising a bracket having members adapted to engage the side and bottom of the lay and a depending member provided with a guideway extending in parallelism with the lay, a rigid slide bar reciprocably mounted in said guideway, means for causing uniform frictional resistance to the movement of said slide bar throughout its extent of reciprocation, a bolt extending longitudinally of through said slide bar, picker stick engaging members formed entirely of sluggishly flexible material clamped by said bolt against the ends of said slide bar and extending laterally therefrom into the path 45 of the picker stick and adapted to bend

when engaged by the picker stick and gradually to check its movement in each direction without causing the picker stick to rebound.

5. In a loom comprising a lay, a picker stick, and means for actuating the same, a metal bracket secured to the lay and having a channel extending in parallelism with the lay, a slide bar reciprocably mounted in said channel, an extended bearing member resting upon said slide bar held against movement longitudinally of the channel and movable toward the bottom of the channel, a yoke secured to the walls of said channel, resilient means intermediate said yoke and said bearing member, means for adjusting the compression of said resilient means to adjustably force the bearing member against the slide bar to press the slide bar against the channel bottom whereby the slide bar will be held frictionally clamped between said bearing member and the channel bottom, flexible members carried by the slide bar at each end thereof to be engaged by the picker stick and a check strap overlying said flexible members.

6. In a loom comprising a lay, a picker stick and means for actuating the same, a slide bar movable longitudinally of the lay, means secured to the lay for causing frictional resistance to the movement of the slide bar uniform throughout the range of said movement, a plurality of short pieces of scrap material abutting and projecting laterally from the ends of the slide bar, a check strap overlying the said pieces of material at its ends and extending parallel with the slide bar, and a bolt passing through the superimposed ends of the check strap and pieces of material, and longitudinally through the slide bar, and clamping the whole together.

In testimony whereof, I have signed my name to this specification.

ISAAC T. PROSSER.
